UNITED STATES PATENT OFFICE.

WILLIAM A. WOODS, OF KAUKAUNA, AND GEORGE H. DREWSSEN, OF FORT ATKINSON,
WISCONSIN.

ADJUSTABLE HOOK.

1,188,227.

Specification of Letters Patent. Patented June 20, 1916.

Application filed September 25, 1915. Serial No. 52,713.

To all whom it may concern:

Be it known that we, WILLIAM A. Woods and GEORGE H. DREWSSEN, citizens of the United States of America, WILLIAM A.

5 Woods, residing at Kaukauna, in the county of Outagamie, and GEORGE H. DREWSSEN residing at Fort Atkinson, in the county of Jefferson and State of Wisconsin, have invented certain new and useful Improvements in Adjustable Hooks, of which the following is a specification.

This invention relates to improvements in adjustable hooks.

The object of the invention is to provide a construction which will afford means for adjustably mounting a hook so that the latter may be conveniently moved back and forth to gain access to an adjacent hook when it is desired to remove or hang a garment.

A further object of the invention is to provide a specific form of hook which is particularly adapted to operate in connection with a support.

25 The invention also comprehends improvements in the details of construction and arrangement of parts which will be herein-after described and particularly pointed out in the claim.

30 In the drawings: Figure 1 is a perspective view of our invention. Fig. 2 is a cross section on the line 2—2, of Fig. 1. Fig. 3 is a detail perspective view of one of our improved hooks. Fig. 4 is a similar view of a 35 slightly different form of hook.

The numeral 1 indicates a base bar formed in its front portion with an open slot 2, which communicates with an enlarged guide slot 3. The base bar may be formed 40 by cutting the enlarged guide slot in the face of the rail, and then attaching two spaced face plates over the front of the rail to provide the slot 2.

The hook we employ is formed from a 45 single piece of wire. One end 4 of the wire is bent over at 5 to provide an eye, and is extended transversely at an incline as at 6, and rebent at 7 to provide a second eye, forming essentially a figure eight. This

portion provides a base 8, said base being 50 slidably mounted in the guide slot 3 as clearly shown. The rebent portion 7, terminates about on a center line drawn horizontally through the base and from this rebent portion 7, the wire is bent outwardly at 55 a right angle to form the upper member 9, of the hook proper. The outer end of the upper member is rebent at 10, and the wire is extended substantially parallel with the upper member 9, to form the lower member 11, 60 of the hook proper. The rear end of the lower member 11, is bent to form a partial ring or supplemental hook 12, the end 13 of the wire terminating under the lower member 11. The rear of the ring 12, is in a different vertical plane than the base 8, of the hook, and abuts against the face of the base bar 1, which forms a support for the hook 65 when in operation.

The hook may be constructed as shown in 70 Fig. 4. That is, the base is the same as that previously described, but the hook proper 15, is formed by extending the end of the wire outwardly and upwardly as shown.

When in use, the base portion 8 of the 75 hook is mounted in the guide slot 3, the upper member extending through the slot 2, while the rear surface of the ring 12, bears against the face of the bar 1. Obviously, when the hook is thus supported it may be 80 slid back and forth to gain access to an adjoining hook, and yet by having the bent portions 5 and 7 of such width as to engage the inner walls of the guide slot, and the rear of the ring 12, impinge the bar 1, the 85 hook will support heavy weights.

The kernel of this invention resides in the formation of the hook from a single piece of wire, and more particularly the base portion 8. By bending the wire in the form 90 of a figure eight, it affords great rigidity and the wire will stand considerable strain.

What we claim is:—

In combination, a wall support provided with an open transverse slot, the rear portion of which is enlarged to provide two inner bearing walls adjacent the open portion of the slot, a support formed from a single

2
piece of metal and provided with a base and a hook, one end of the metal being bent upon itself and extended at an angle to form a central connecting bar, the opposite 5 end of said bar being rebent upon itself to a point adjacent said central connecting bar, at which point the metal is bent outwardly to extend through the open slot and forms the hook, the bent portions at the ends of 10 the connecting bar engaging the inner bearing walls of the wall support, the metal at the outer end of the hook being rebent upon itself to a point adjacent the front of the

base where said material is bent to engage said front of the base to brace the hook.

15

In testimony whereof we affix our signatures in presence of two witnesses.

WILLIAM A. WOODS.
GEORGE H. DREWSSEN.

Witnesses as to William A. Woods:

H. J. MULHOLLAND,
GEO. H. KELLY.

Witnesses as to George H. Drewsen:

M. J. KERSCHENSTEINER,
O. L. STENGEL.
